UNITED STATES PATENT OFFICE.

JOHN F. SEIBERLING, OF AKRON, OHIO.

CORD-HOLDER FOR GRAIN-BINDERS.

SPECIFICATION forming part of Letters Patent No. 430,697, dated June 24, 1890.

Application filed July 13, 1888. Serial No. 279,816. (No model.)

To all whom it may concern:

Be it known that I, JOHN F. SEIBERLING, of Akron, county of Summit and State of Ohio, have invented a new and useful Improvement in Cord-Holders for Grain-Binders, of which the following is a full, clear, and exact description, reference being had to the accompanying drawings, making part of this specification.

10 My invention relates to that class of cord-holders in which a notched rotating-wheel is employed in connection with a yielding shoe or clamp for holding the ends of the band received from the needle, and more particularly 15 to the construction of the holder whereby the clamping-surface is shortened to allow the cut ends of the band to be released and drawn out of the holder in the act of discharging the bundle and of cutting the band at the 20 needle end thereof, thereby preventing an accumulation of short cut ends in and the consequent clogging of the holder, as herein-after described and claimed.

In the accompanying drawings, Figure 1 25 shows in rear elevation my improved cord-holder and other parts of the binder mechanism in connection with which it operates. Fig. 2 is a side view, partly in section of the parts shown in Fig. 1, looking from the stubble side. Fig. 3 is a side elevation of the 30 cord-holder, wheel, and shoe, showing also the pinion for rotating and the delay-cam for holding the wheel in the intervals of its movement. Fig. 4 is a perspective view, and Fig. 35 5 a plan view, of the shoe detached; and Fig. 6 is a face view of the notched wheel or rim, showing the pinion and delay-cam.

A indicates the knotter-actuating shaft; A', the knotter-actuating cam and gear wheel fast 40 on said shaft; B, the knotter stand or frame suspended from the shaft A and supporting the knotter breast-plate C, the latter being attached to flanges or feet on the lower end of said stand B, and D is a pivoted frame or 45 sleeve, in which the knotter-shaft E is journaled, said frame D being connected by a pivot d to the frame or stand B at a point above the shaft A to permit the knotter E' on the lower end of shaft E to be vibrated

toward and away from the plane of the cam-wheel A. The frame or sleeve D is provided with arms or bosses e e', one of which has the knife F secured to it to vibrate with the frame D, and the other a spring-plate F', which acts in the revolution of the knotter to 55 close the movable jaw upon the fixed one for clamping the ends of the band.

G indicates the needle.

The above-named parts are described and shown in connection with my improved cord-holder; but any usual construction and arrangement of said parts may be employed.

Upon the knotter shield or breast-plate C, or other suitable support, is formed or otherwise secured a lug or short upright H, supporting an inclined stud-shaft h, on which the cord-holder wheel I is journaled. This wheel is made, preferably, in the form of a short hollow cylinder secured at one end to a pinion J, which actuates it, the pinion J having formed upon or secured to its forward face a delay-cam plate J' for engaging the peripheral flange on the cam and gear wheel A', and holding the wheel I and its pinion stationary in the intervals between their intermittent rotating movements. The wheel or rim I is shown provided in its outer face or end with cord-notches i i' i'', and the delay-cam plate or disk J' is shown provided with segmental depressions, forming delay-surfaces corresponding in number to the number of cord-notches in the wheel I. The outer end of the wheel or rim I has a peripheral flange or rib I' formed upon it, which is cut away at the cord-notches, and which enters 85 and carries the portion of band material received from the needle into the shoe indicated at K, and also serves to hold the shoe on the cord-wheel. The shoe or cord clamp K is made concave on its upper face to conform to the diameter of the wheel or rim I, and is grooved at k' to receive the rib I', and its clamping-face k is made of a length just sufficient to extend from one to another of the notches in the cord-holder wheel or rim 90 I—that is to say, supposing the cord to enter the notch i in said wheel, it is carried by the partial rotation of the wheel and by the ac-

tion of the portion of the rib I' in rear of said notch into the shoe, where it is clamped between the outer face or periphery of the rim or crown-wheel and shoe, and is moved inward 5 toward the knotter (in the direction indicated by the arrow) for yielding cord thereto until it reaches the end k² of the clamping-face of the shoe, when the movement of the wheel ceases just as the knotter has completed its 10 revolution for forming the knot and is ready to be vibrated for causing the knife to cut the band material and for drawing itself out of, and the end of the band through, the loop. In this movement of the cord-wheel the portion 15 or end of the band extending from the needle is left held between the clamp and wheel extending from the notch i to the notch i' of the latter. At the next movement or partial rotation of the wheel I the portion or 20 end of the cord held, as above described, is carried to the discharge end k² of the shoe and is freed just as the knife is vibrated to cut the cord, and, instead of being cut with the portion at that time connecting with the 25 needle, is drawn out of the cord-holder, attached to, and is discharged, with the bundle, instead of being cut off and left in the cord-holder, as it has been in constructions heretofore in use.

30 By the construction described all clogging of the holder by cut ends of the band material is avoided, and the resistance to the action of the knife is reduced, as the knife is required to cut but one cord instead of two.

35 The knife employed is hook-shaped, and has its cutting-edge on the inner face of its hooked end, so as to cut the band as it is vibrated outward or away from the cam and gear-wheel A' with the knotter, as the latter, 40 after having formed the knot, is vibrated for withdrawing it from the loop and for drawing the ends of the band through said loop.

The shoe or clamp is provided at its inner receiving end with a fork or two projecting 45 curved prongs l and l', the first named serving as a guard to cover the notch in the cord-wheel at that point and prevent the cord from the needle from entering and being caught therein, and the other l', which di- 50 verges from the prong l, serving in connection with the latter to guide the cord to the outer receiving-notch. The shoe has at its outer end an outwardly-projecting spur m, inclined on its upper face, upon which the 55 cord is laid by the needle, and which serves to deflect said cord and carry it into the notch in the wheel. Said outer end of the shoe is also provided with a curved prong or hook m', which extends around the notch in 60 the wheel, its upper end resting in contact or in close proximity with the rib I' above said notch for preventing the cord from the needle from wrapping around the wheel and insuring its escape through the succeeding 65 notch.

The clamp or shoe K is provided on its lower face with a spur k³, which enters a perforation in the outer free end of a flat spring L, attached to a suitable support on the breast-plate, and which serves to uphold the 70 shoe in yielding contact with the cord-holder wheel.

In another application filed April 21, 1888, Serial No. 271,381, I have shown a construction of cord-holder resembling that herein 75 shown and described, but differing from it in that the clamping-surface of the cord clamp or shoe is not therein restricted to a single clamping-face only, (said face extending only from center to center of or between two adjacent cord-notches of the crown-disk,) nor to a specific arrangement of the guard or cord guide on the inner end of said clamp, which constitute the salient features of the invention herein claimed.

Having described my invention, I claim as new—

1. The combination, in a grain-binder, of a knotter, a rotary cord-holder wheel or disk having a series of cord-notches, and having 90 an intermittent movement imparted to it during each revolution of the knotter, a knife operating between the knotter and said wheel to cut the cord, and a clamp or shoe arranged to engage the cord on the side of the wheel 95 away from the knotter, the side of the wheel adjacent to the knotter being unobstructed to permit the notch to carry the cord toward the terminal end of the shoe, and the intermittent movement of the wheel being of sufficient extent and timed relative to the shoe to cause the notch to carry the end of the cord past the end of the clamping-surface of said shoe and release it in advance of the action 100 of the knife to cut the cord, substantially as 105 described.

2. The combination, with a crown-disk cord-holder having a series of cord-notches, of a clamp or shoe having a clamping-surface bearing against the disk between two of said 110 notches only, and a guard for preventing the cord from entering the notch in the disk at the end of the shoe nearest the knife while the needle lays the cord in the notch at the opposite end of the shoe, whereby the end of 115 the cord extending around the bundle is released in advance of the action of the knife on the cord, substantially as described.

3. The combination of a crown-disk cord-holder having a series of notches to receive the cord, a cord clamp or shoe having a clamping-surface bearing against the face of said disk between two of said notches only, said disk and shoe being provided one with a groove and the other with a retaining-flange, 120 and a guard at the inner end of said shoe for preventing the cord from entering the notch nearest the knotter while the needle lays the cord in the open notch in the opposite side 125 of said disk, substantially as described. 130

4. The combination of the crown-disk cord-holder having a series of notches, the clamp or shoe E, having a clamping-surface extending only between two of said notches, the
5 guard e³ at the inner end of said shoe for preventing the cord from entering the notch nearest the knotter while the needle lays the cord in the open notch in the opposite side of

said disk, a supporting-spring, the knotter k, and the knife h, substantially as described. 10

In testimony whereof I have hereunto set my hand this 10th day of July, A. D. 1888.

JNO. F. SEIBERLING.
